UNITED STATES PATENT OFFICE.

JAMES G. MILLER, OF PRINCETON, WEST VIRGINIA.

MAIL-BAG CATCHER.

1,217,806.

Specification of Letters Patent. Patented Feb. 27, 1917.

Application filed May 5, 1916. Serial No. 95,666.

To all whom it may concern:

Be it known that I, JAMES G. MILLER, a citizen of the United States, residing at Princeton, in the county of Mercer and State 5 of West Virginia, have invented new and useful Improvements in Mail-Bag Catchers, of which the following is a specification.

This invention is an improved mail bag catcher or mail hook, for use on a mail car 10 for removing mail bags from cranes, as the train passes stations and avoids the necessity of stopping the train in order to receive the mail, one object of the invention being to effect an improvement in the construction 15 of the hook by increasing the length of the arm thereof and thereby enable the mail cranes to be stationed at a sufficient distance from the track to provide safe clearance for the locomotive and avoid injury to the engineer or fireman, another object of the invention being to provide improved means 20 for holding and adjusting the hook and greatly facilitating the use of the device in catching a mail bag.

25 The invention consists in the features of construction, combination, and arrangement of devices, hereinafter fully described and claimed.

In the accompanying drawings:—

30 Figure 1 is a perspective view of a mail bag catcher constructed and arranged in accordance with my invention showing the same in place on a mail car.

Figs. 2 and 3 are detail views.

35 In the embodiment of my invention, I provide a shaft 1 which extends across the door opening and is mounted in bearings 2 which are secured on the door facing. The shaft has a diametrically enlarged portion 3 near 40 its rear end and also has a widened portion 4 which is provided with a transverse opening 5.

The metal hook 6 comprises a lever 6^a having a handle 11 in line therewith and at 45 its inner end, an arm 6^b at the outer end of the lever arranged at an angle thereto, a bill 9 and a bight 10 connecting the inner end of the bill to the inner end of the arm. The bill, bight, arm, lever and handle are 50 all arranged in a common plane. The lever extends through the opening 5 of the shaft and is mounted on a pivot 7 so that the hook is arranged for annular movement in a plane parallel with the shaft and is also arranged 55 in a common plane with the shaft. The bill 8 of the hook is provided with an extension

9 which considerably increases the length of the bill and thus gives the mail hook a greater reach to one side of the mail car and thus enables the hook to catch a mail bag 60 suspended from a mail crane, spaced a sufficient distance from the track to afford safe clearance with the locomotive and prevent injury to the engineer or fireman should they be looking out of the cab window while passing a station. The mail bag is caught by the hook at the center in the usual way and lodges in the bight 10 of the hook. 65

The operation of the mail bag catcher is as follows. When approaching a mail bag 70 which is supported by a crane, the mail man stationed in the car grasps the handle 11 and pushes the same forwardly thereby turning the hook, to the position indicated in dotted lines in Fig. 1, and causing the hook to bear 75 against the shoulders 12 formed at the diagonally opposite ends of the opening 5, thus putting the strain of operation on the shoulders and also on the pivot pin 7. The mail man holds the outer end or arm 8 of the hook 80 at the proper height to catch the bag, the shaft 1 turning in its bearings and permitting this to be very readily done, and after catching the bag in the bight of the hook, he then turns the same inwardly to 85 safely land the bag in the car. The shaft 1 is provided with a snap chock 13 behind the rear bearing 2 and which coacts with the enlarged portion 3 of the shaft to secure the shaft horizontally. 90

Having described the invention, what is claimed is:

1. In a mail bag catcher, the combination of a horizontally arranged shaft mounted for turning movement and a hook comprising a lever for manual operation having a handle in line therewith at its inner end, an arm at the outer end of the lever arranged at an angle thereto, a bill having an extension at its outer end and a bight connecting the inner end of the bill to the inner end of the arm, said lever being pivotally mounted on the shaft for annular movement in a plane parallel with the shaft and arranged in a common plane therewith. 100

2. In a mail bag catcher, the combination of a horizontally arranged shaft mounted for turning movement and a hook comprising a lever for manual operation and having a handle in line therewith at its inner end, an arm at the outer end of the lever arranged at an angle thereto, a bill having an 110

extension at its outer end and a bight connecting the inner end of the bill to the inner end of the arm, said lever being pivotally mounted on the shaft for annular movement in a plane parallel with the shaft and arranged in a common plane therewith, and the shaft being provided with a widened intermediate portion having an opening through which the lever of the hook extends

and also having shoulders at diagonally opposite ends of said openings against which the hook bears when in position to catch a mail bag.

In testimony whereof I affix my signature.
JAS. G. MILLER.
